(57) **ABSTRACT**

Provided is an electric die casting machine capable of achieving high injection speed and high boost pressure. An injection unit (100) is provided with an electric servomotor (104) for injection in a first stage, a ball screw mechanism (110) (motion converting mechanism in the first stage) for converting rotational motion of the electric servomotor for injection in the first stage into rectilinear motion of a linear motion body (106), electric servomotors (111 and 112) for injection in a second stage, mounted on the linear motion body, a crank mechanism (113 and 116) (motion converting mechanism in the second stage) for converting rotational motion of the electric motor servomotor for injection in the second stage into rectilinear motion of an injection plunger (118), and a control unit (400) for controlling driving of each electric servomotor for injection. The control unit drives only the electric servomotor (104) for injection in the first stage independently in a low-speed injection step, and drives both the electric servomotor (104) for injection in the first stage and the electric servomotors (111 and 112) for injection in the second stage simultaneously in a high-speed injection step and a pressure intensification step.

DIE CASTING MACHINE

TECHNICAL FIELD

The present invention relates to a die casting machine provided with an injection unit driven by electric servomotors, and particularly relates to a motion converting mechanism for converting rotational motion of electric servomotors into rectilinear motion of an injection plunger.

BACKGROUND ART

In a die casting machine, a molten metal material (metal melt) such as an Al alloy or a Mg alloy melted in a melting furnace is measured and scooped every shot by a ladle. The scooped metal melt is poured into an injection sleeve. The metal melt is then injected/filled into a cavity of a mold in accordance with forward movement of an injection plunger. Thus, a product is obtained.

The casting procedure of the die casting machine includes an injection step consisting of a low-speed injection step and a high-speed injection step following the low-speed injection step, and a pressure intensification step following the high-speed injection step. The high-speed injection step requires a higher injection speed than that of injection molding of a plastic material. In addition, the pressure intensification step requires a higher boosting force than that of injection molding of a plastic material. Accordingly, a comparatively large-scale hydraulic drive source is heretofore generally used as a drive source for injection/pressure boosting. In addition, since the comparatively large-scale hydraulic drive source is provided, the hydraulic drive sources are often used as drive sources for opening/closing a mold or extruding a cast product.

However, such a hydraulic die casting machine is apt to contaminate a factory with oil. Therefore, there is an increasing request for an electric die casting machine to keep a factory clean. In order to cope with such a request, the present applicant has already proposed a die casting machine including a crank mechanism in which a first arm is rotationally driven by an electric servomotor and an injection plunger is rotatably linked with a front end of a second arm one end of which is rotatably linked with the first arm (see Patent Document 1). In this die casting machine, the crank mechanism is set in advance so that the high-speed injection step can be carried out in a rotational angle range where the relative speed of the injection plunger is the highest, and the pressure intensification step can be carried out in a rotational angle range where the magnifying ratio of force acting on the injection plunger is the highest. Thus, products can be cast without use of any hydraulic drive source.

Patent Document 1: JP-A-2008-114246

SUMMARY OF THE INVENTION

Problem that the Invention is to Solve

However, according to the technique disclosed in Patent Document 1, only a pair of an electric servomotor for injection and a crank mechanism to be rotationally driven by the electric servomotor is provided. Therefore, there is a problem that it is difficult to apply the technique to a large-scale die casting machine which is required to further increase the injection speed and further increase the boosting pressure.

The present invention was developed in consideration of the aforementioned problem. An object of the invention is to

2

provide an electric die casting machine which can obtain a high injection speed and a high boosting pressure.

Means for Solving the Problem

In order to attain the object, a first configuration of the invention is made to include: an electric servomotor for injection in a first stage, which is fixed to a motor mounting plate; a motion converting mechanism in the first stage, which converts rotational motion of the electric servomotor for injection in the first stage into rectilinear motion of a linear motion body; an electric servomotor for injection in a second stage, which is mounted on the linear motion body; a motion converting mechanism in the second stage, which converts rotational motion of the electric servomotor for injection in the second stage into rectilinear motion of an injection plunger; and a control unit which controls driving of each of the electric servomotors for injection; wherein: the control unit drives only the electric servomotor for injection in the first stage independently in a low-speed injection step, and drives both the electric servomotor for injection in the first stage and the electric servomotor for injection in the second stage simultaneously in a high-speed injection step and a pressure intensification step.

With this configuration, the injection plunger can be moved forward in accordance with the total speed of the forward speed of the linear motion body caused by the rotational driving of the electric servomotor for injection in the first stage and the forward speed of the injection plunger caused by the electric servomotor for injection in the second stage. Thus, the injection speed can be made higher. In addition, the injection plunger can be moved forward in accordance with the total pressure of the pressure of the linear motion body caused by the rotational driving of the electric servomotor for injection in the first stage and the pressure of the injection plunger caused by the rotational driving of the electric servomotor for injection in the second stage. Thus, the injection pressure and the boosting pressure can be increased.

A second configuration of the invention is made in such a manner that one of the motion converting mechanism in the first stage and the motion converting mechanism in the second stage is a crank mechanism which includes a first arm and a second arm, the first arm being rotationally driven by the electric servomotor for injection in the first stage or the electric servomotor for injection in the second stage, the second arm having one end rotatably linked with the first arm and the other end rotatably linked with the linear motion body or the injection plunger.

The crank mechanism is different from a ball screw mechanism. A movable part of the crank mechanism does not slide in the axial direction of a shaft and the crank mechanism has high tolerance against dust. Accordingly, when the crank mechanism is applied to the die casting machine in which fine dust of a metal material or atomized liquid of a release agent sprayed to a releasing surface of a mold may fly around in operation, the life of the motion converting mechanism can be extended, and the maintenance thereof can be made easier.

A third configuration of the invention is made in such a manner that an initial position of the crank mechanism is set so that the high-speed injection step can be carried out in a rotational angle range of the first arm where a relative speed of the linear motion body or the injection plunger is the highest, and the pressure intensification step can be carried out in a rotational angle range of the first arm where a magnifying ratio of force acting on the linear motion body or the injection plunger is the highest.

plunger 118 is rotatably pin-connected to a front end of the second arm 116 through a connecting pin 117. In order to avoid bad effect of dust or atomized liquid, it is particularly desirable that a sealed bearing is used as the bearing of each pin-connection portion. In addition, rotary encoders 121, 122 and 123 as rotation angle detecting sensors are provided in the first to third injection servomotors 104, 111 and 112 respectively.

As shown in FIG. 4, the first injection servomotor 104 is constituted by a casing 104a, a cylindrical motor stator 104b fixed to an inner surface of the casing 104a, a motor coil 104c wound around an outer circumference of the motor stator 104b, a cylindrical motor rotor 104d disposed in the motor stator 104b, and a motor magnet 104e attached to an outer surface of the motor rotor 104d. The screw shaft 108 is connected to an inner surface of the motor rotor 104d through a connecting member 119. Accordingly, when a motor drive current outputted from the driver circuit 401 based on a command signal of the control unit 400 is applied to the first injection servomotor 104, the screw shaft 108 is rotationally driven with the motor rotor 104d and the connecting member 119 so that the linear motion body 106 is moved in the axial direction of the screw shaft 108 with the nut body 109 on down to the screw shaft 108.

Likewise, as shown in FIG. 4, the second injection servomotor 111 is constituted by a casing 111a, a cylindrical motor stator 111b fixed to an inner surface of the casing 111a, a motor coil 111c wound around an outer circumference of the motor stator 111b, a cylindrical motor rotor 111d disposed in the motor stator 111b, and a motor magnet 111e attached to an outer surface of the motor rotor 111d, and the third injection servomotor 112 is constituted by a casing 112a, a cylindrical motor stator 112b fixed to an inner surface of the casing 112a, a motor coil 112c wound around an outer circumference of the motor stator 112b, a cylindrical motor rotor 112d disposed in the motor stator 112b, and a motor magnet 112e attached to an outer surface of the motor rotor 112d. The motor rotors 111d and 112d of the second and third injection servomotors 111 and 112 are connected to the first arm 113. Accordingly, when a motor drive current outputted from the driver circuit 401 based on a command signal of the control unit 400 is applied to the second and third injection servomotors 111 and 112, the first arm 113 is rotationally driven by the motor rotors 111d and 112d so that the plunger 118 is moved in the axial direction of the screw shaft 108 with the second arm 116 connected to the first arm 113.

A front end portion of the plunger 118 is slidably received in a sleeve 201a fixed to a fixed die plate 201 which is a constituent of the mold clamping unit 200 as shown in FIGS.

5 to 7. In addition, a melt injection hole 201b communicating with the inside of the sleeve 201a is provided in the fixed die plate 201. Thus, when the plunger 118 is moved forward after melt is injected into the sleeve 201a through the melt injection hole 201b in the state that the plunger 118 is moved back, the melt injected into the sleeve 201a is injected into a mold cavity 210 which is formed by clamping a fixed mold 208 and a movable mold 209, through a runner 208a provided in the fixed mold 208. In this manner, die-casting of a molded piece with a desired shape is performed.

This point will be described more in detail. In a standby position shown in FIG. 5, the nut body 109 of the ball screw mechanism 110 has moved to a base end side (first injection servomotor 104 side) of the screw shaft 108, and the first connecting shaft 115 of the first arm 113 has been stopped in an upper right direction of 45° in view from the rotation center of the first arm 113. As soon as an injection step is started, a motor drive current outputted from the driver circuit

401 based on a command signal of the control unit 400 is applied to the first injection servomotor 104 so that the motor rotor 104d and the screw shaft 108 rotate integrally. In this manner, as shown in FIG. 6, the nut body 109, the linear motion body 106, the second and third injection servomotors 111 and 112, and the plunger 118 move integrally to the front end side (mold side).

When the amount of rotation of the first injection servomotor 104 reaches a predetermined value, a motor drive current outputted from the driver circuit 401 based on a command signal of the control unit 400 is applied to the second and third injection servomotors 111 and 112 so that the motor rotors 111d and 112d and the first arm 113 rotate integrally. In this manner, as shown in FIG. 7, the second arm 116 and the plunger 118 move integrally to the front end side. In this embodiment, the second and third injection servomotors 111 and 112 are rotationally driven until the first connecting shaft 115 reaches an upper left direction of 45° in view from the rotation center of the first arm 113. In this manner, the second arm 116 and the plunger 118 can be moved to the front end side at a high speed when the first connecting shaft 115 is moved to the upper left direction of 45° from the upper right direction of 45° in view from the rotation center of the first arm 113.

Accordingly, as shown in FIG. 8, the forward moving speed of the plunger 118 is low when the plunger 118 is driven only by the driving force of the first injection servomotor 104, and high when the plunger 118 is driven by the total driving force of the first to third injection servomotors 104, 111 and 112.

In this manner, the plunger 118 is driven by the first to third injection servomotors 104, 111 and 112 in the die casting machine according to this embodiment. Accordingly, the structure of the die casting machine can be simplified because any accumulator and any hydraulic oil pipeline provided in the background art are not required, while the speed of the plunger 118 can be controlled strictly. In addition, the driving force of the second and third injection servomotors 111 and 112 is transmitted to the plunger 118 through the crank mechanism constituted by the first arm 113 and the second arm 116. Thus, a predetermined injection speed (e.g. maximum speed 6,000 mm/sec) and a predetermined thrust (e.g. 160 KN) required for injecting a melt and boosting the pressure thereof can be obtained.

Although the two injection servomotors 111 and 112 are mounted on the linear motion body 106 in the aforementioned embodiment, it will be enough if one of the injection servomotors is provided when there is an excess of the moving speed or the thrust of the plunger 118.

In addition, in the aforementioned embodiment, the ball screw mechanism 110 is used as a motion converting mechanism for converting the rotational motion of the first injection servomotor 104 into rectilinear motion of the linear motion body 106, the second injection servomotor 111 and the third injection servomotor 112. In place of that configuration, it may be possible to use a crank mechanism constituted by a first arm which can be rotationally driven by the first injection servomotor 104, a second arm which has one end rotatably pin-connected to the first connecting shaft of the first arm and the other end rotatably pin-connected to the linear motion body 106, and sealed bearings which are provided in the pin-connection portions. According to such a configuration, the tolerance of the motion converting mechanism against dust or atomized liquid can be enhanced so that the die casting machine can be made low in cost and easy in maintenance.

Next, description will be made on the mold clamping unit 200 of the die casting machine according to the embodiment.

As shown in FIGS. 9 and 10, the mold clamping unit 200 according to the embodiment has a fixed die plate 201, a tail stock 202, a plurality of tie bars 203, a movable die plate 204, a toggle link mechanism 205, an electric servomotor (mold clamping servomotor) 206, and a crank mechanism 207. The fixed die plate 201 and the tail stock 202 are fixed onto a not-shown bed of the machine. The opposite ends of the tie bars 203 are fixed to the fixed die plate 201 and the tail stock 202. The movable die plate 204 is guided by the tie bars 203 so as to move forward/backward between the fixed die plate 201 and the tail stock 202. The toggle link mechanism 205 links the tail stock 202 with the movable die plate 204. The electric servomotor 206 is mounted on the tail stock 202 and serves as a drive source for opening/closing molds and clamping the molds. The crank mechanism 207 converts rotational motion of the electric servomotor 206 into rectilinear motion and transmits the rectilinear motion to the toggle link mechanism 205. The fixed mold 208 is mounted on the fixed die plate 201, and the movable mold 209 is mounted on the movable die plate 204. A rotary encoder (not shown) serving as a rotation angle detecting sensor is provided in the mold clamping servomotor 206.

The toggle link mechanism 205 is constituted by a B link 211 which has one end rotatably pin-connected to the tail stock 202, an A link 212 which has one end rotatably pin-connected to the movable die plate 204 and the other end pin-connected to the other end of the B link 211 so as to rotate relatively, a cross head 213 to which the driving force of the electric servomotor 206 is applied through the crank mechanism 207, and a C link 214 which has one end rotatably pin-connected to the cross head 213 and the other end pin-connected to an intermediate portion of the B link 211 so as to rotate relatively. The reference sign O1 represents a pin connection portion of the B link 211 to the tail stock 202; O2, a pin connection portion of the A link 212 to the B link 211; O3, a pin connection portion of the C link 214 to the B link 211; O4, a pin connection portion of the A link 212 to the movable die plate 204; and O5, a pin connection portion of the C link 214 to the cross head 213. It is desirable that each pin connection portion O1 to O5 is provided with a sealed bearing in order to avoid bad effect of dust or atomized liquid. Thus, the toggle link mechanism 205 according to this embodiment has the A link 212, the B link 211 and the C link 214 and serves as a link mechanism with a five-point support structure including five pin connection portions O1 to O5. However, the gist of the invention is not limited thereto. It is a matter of course that a toggle link mechanism of another type may be provided.

Similarly to the aforementioned first to third injection servomotors 104, 111 and 112, a closed type built-in motor which is constituted by a casing, a cylindrical motor stator fixed to an inner surface of the casing, a motor coil wound around an outer circumference of the motor stator, a cylindrical motor rotor disposed in the motor stator and a motor magnet attached to an outer surface of the motor rotor and which has maximum torque higher than 300% of rated torque is used as the mold clamping servomotor 206.

The crank mechanism 207 is constituted by a first arm 221 whose rotating shaft 221a is connected to the motor rotor of the mold clamping servomotor 206 and a second arm 223 which has one end rotatably pin-connected to a first connecting shaft (eccentric shaft) 222 formed in the first arm 221 and the other end rotatably pin-connected to a second connecting shaft 224 formed in the cross head 213. It is desirable that a sealed bearing is provided in each of pin connection portions O7 and O8 so as to more reduce the effect of dust or the like.

FIG. 9 is a view showing the state of the crank mechanism 207 in a mold opening state, and FIG. 10 is a view showing the state of the crank mechanism 207 in a mold closing state. As shown in FIG. 9, in the mold opening state, the pin connection portion O7 between the first connecting shaft 222 and the second arm 223 and the pin connection portion O8 between the second arm 223 and the cross head 213 are disposed on the opposite sides of the rotation center O6 of the mold clamping servomotor 206 (first arm 221) so that the crank mechanism 207 is folded. On the other hand, in the mold closing state, as shown in FIG. 10, the rotation center O6 of the mold clamping servomotor 206 (first arm 221), the pin connection portion O7 between the first connecting shaft 222 and the second arm 223 and the pin connection portion O8 between the second arm 223 and the cross head 213 are disposed in this order so that the crank mechanism 207 is unfolded.

The control unit 400 stores rotation angles of the first arm 221 for controlling the drive torque of the mold clamping servomotor 206. In the range of the stored rotation angles, the mold clamping servomotor 206 is driven to output torque higher than rated torque, for example, to output maximum torque. In the other angle range, the mold clamping servomotor 206 is driven to output torque not higher than the rated torque. Thus, a required mold clamping force can be given to the mold clamping unit 200 at required timing.

For example, assume that the rotation angle θ of the first arm is set as 0° when the pin connection portion O7 between the first connecting shaft 222 and the second arm 223, the rotation center O6 of the first arm 221 and the pin connection portion O8 between the second arm 223 and the cross head 213 are disposed in a straight line in this order (see FIG. 9). In addition, as shown in FIG. 11, assume that the rotation angle θ of the first arm 221 is set as α_1° when the fixed mold 208 and the movable mold 209 are closed, and the rotation angle θ of the first arm 221 is set as β_1° when a required mold clamping force is given between the fixed mold 208 and the movable mold 209. In the angle range of $\alpha_1^\circ \leq \theta \leq \beta_1^\circ$, the mold clamping servomotor 206 is driven to output torque higher than the rated torque, for example, to output maximum torque as shown by a curve Tm1. In the other angle range than $\alpha_1^\circ \leq \theta \leq \beta_1^\circ$, the mold clamping servomotor 206 is driven to output torque not higher than the rated torque as shown by a curve Ts1. Thus, the fixed mold 208 and the movable mold 209 can be closed quietly, and a mold clamping force P1 required for performing the injection step can be given between the fixed mold 208 and the movable mold 209.

According to such a configuration, the crank mechanism 207 provided with the sealed bearings is used as a motion converting mechanism for converting rotational motion of the mold clamping servomotor 206 into rectilinear motion of the movable die plate 204, so that tolerance against dust or atomized liquid can be enhanced as compared with that in the case where a ball screw mechanism is used. It is therefore unnecessary to cover the periphery of the crank mechanism 207 with a closed structure, and it is possible to reduce labor required for maintenance. Thus, the cost of the die casting machine can be made lower and the maintenance thereof can be made easier. In addition, a motor whose maximum torque is higher than 300% of rated torque is provided as the mold clamping servomotor 206, while rotation angles $0 = \alpha_1^\circ$ and β_1° of the first arm 221 are set in the control unit 400 to control driving of the mold clamping servomotor 206. The mold clamping servomotor 206 is driven to output torque higher than the rated torque in the angle range of $\alpha_1^\circ \leq \theta \leq \beta_1^\circ$, and the mold clamping servomotor 206 is driven to output torque not higher than the rated torque in the other angle range than $\alpha_1^\circ \leq \theta \leq \beta_1^\circ$. Thus, a required mold

clamping force can be obtained with a small motor whose rated torque is small, so that the die casting machine can be made smaller in size and lower in cost.

Next, description will be made on the ejecting unit 300 of the die casting machine according to the embodiment.

As shown in FIGS. 12 to 15, the ejecting unit 300 according to the embodiment has an ejecting plate 301, a plurality of ejecting pins 302 planted in the ejecting plate 301, an electric servomotor (ejecting servomotor) 303 serving as a drive source of the ejecting plate 301, and a crank mechanism 304 for converting rotational motion of the ejecting servomotor 303 into rectilinear motion and transmitting the rectilinear motion to the ejecting plate 301. The ejecting plate 301 and the crank mechanism 304 are disposed in an ejecting unit receiving space 305 formed in the movable die plate 204. The ejecting pins 302 pass through and are disposed in pin insertion holes 306 provided in the movable plate 204. Incidentally, a rotary encoder (not shown) serving as a rotation angle detecting sensor is provided in the ejecting servomotor 303.

In the same manner as the mold clamping servomotor 206, a closed type built-in motor which is constituted by a casing, a cylindrical motor stator fixed to an inner surface of the casing, a motor coil wound around an outer circumference of the motor stator, a cylindrical motor rotor disposed in the motor stator and a motor magnet attached to an outer surface of the motor rotor and which has maximum torque higher than 300% of rated torque is used as the ejecting servomotor 303.

As shown in FIG. 12, the crank mechanism 304 is constituted by a first arm 311 connected to the motor rotor of the ejecting servomotor 303, a second arm 313 one end of which is rotatably pin-connected to a first connecting shaft 312 and the other end of which is rotatably pin-connected to the ejecting plate 301, and not-shown sealed bearings provided in pin connection portions O10 and O11 respectively.

FIG. 13 is a view showing a state of the crank mechanism 304 before the start of ejecting. FIG. 14 is a view showing a state of the crank mechanism 304 during the ejecting. FIG. 15 is a view showing a state of the crank mechanism 304 after completion of the ejecting. As shown in FIG. 13, before the start of ejecting, the pin connection portion O10 between the first connecting shaft 312 and the second arm 313 and the pin connection portion O11 between the second arm 313 and the ejecting plate 301 are disposed on the opposite sides of a rotation center O9 of the ejecting servomotor 303 (first arm 311). When the ejecting servomotor 303 is driven at that state to rotate the first arm 311, front end portions of the ejecting pins 302 are inserted into pin insertion holes 307 provided in the movable mold 209 so as to extrude a molded product with a not-shown ejecting plate of the mold, as shown in FIG. 14. Next, as shown in FIG. 15, the ejecting servomotor 303 is continuously driven until reaching a position where the rotation center O9 of the ejecting servomotor 303 (first arm 311), the pin connection portion O10 between the first connecting shaft 312 and the second arm 313 and the pin connection portion O11 between the second arm 313 and the ejecting plate 301 are disposed in this order. The molded product is then extracted from the movable mold 209. For the ejecting of the molded product, high pressure is required for a period till the molded product is released from the movable mold 209. In the other period, low pressure may be enough if it can press the ejecting plate 301 independently.

The control unit 400 stores rotation angles of the first arm 311 for controlling the drive torque of the ejecting servomotor 303. In the range of the stored rotation angles, the ejecting servomotor 303 is driven to output torque higher than rated torque, for example, to output maximum torque. In the other angle range, the ejecting servomotor 303 is driven to output

torque not higher than the rated torque. In this manner, a required ejecting force can be given to the ejecting unit 300 at required timing.

For example, assume that the rotation angle θ of the first 5 arm is set as 0° when the pin connection portion O10 between the first connecting shaft 312 and the second arm 313, the rotation center O9 of the first arm 311 and the pin connection portion O11 between the second arm 313 and the ejecting plate 301 are disposed in a straight line in this order 10 (see FIG. 13). In addition, as shown in FIG. 16, assume that the rotation angle θ of the first arm 311 is set as α_2° when the front end portion of a not-shown ejecting plate provided in the mold abuts against the surface of a molded product, and the rotation angle θ of the first arm 311 is set as β_2° when the 15 molded product is released from the movable mold 209. In the angle range of $\alpha_2^\circ \leq \theta \leq \beta_2^\circ$, the ejecting servomotor 303 is driven to output torque higher than rated torque, for example, to output maximum torque as shown by a curve Tm2. In the other angle range than $\alpha_2^\circ \leq \theta \leq \beta_2^\circ$, the ejecting servomotor 303 is driven to output torque not higher than the rated torque as shown by a curve Ts2. Thus, a large ejecting force P2 required for releasing the molded product can be given to the ejecting plate 301.

According to such a configuration, the crank mechanism 25 304 provided with the sealed bearings is used as a motion converting mechanism for converting rotational motion of the ejecting servomotor 303 into rectilinear motion of the ejecting plate 301, so that tolerance against dust or atomized liquid 30 can be enhanced as compared with that in the case where a ball screw mechanism is used. It is therefore unnecessary to cover the periphery of the crank mechanism 304 with a closed structure, and it is possible to reduce labor required for maintenance. Thus, the cost of the die casting machine can be made lower and the maintenance thereof can be made easier. 35 In addition, a motor whose maximum torque is higher than 300% of rated torque is provided as the ejecting servomotor 303, while rotation angles $\theta = \alpha_2^\circ$ and β_2° of the crank are set in the control unit 400 to control driving of the ejecting servomotor 303. The ejecting servomotor 303 is driven to 40 output torque higher than the rated torque, for example, to output maximum torque in the angle range of $\alpha_2^\circ \leq \theta \leq \beta_2^\circ$, and the ejecting servomotor 303 is driven to output torque not higher than the rated torque in the other angle range than $\alpha_2^\circ \leq \theta \leq \beta_2^\circ$. Thus, a required ejecting force can be 45 obtained by use of a small motor whose rated torque is small, so that the die casting machine can be made smaller in size and lower in cost.

Incidentally, in the aforementioned embodiment, configuration is made in such a manner that the ejecting unit 300 is 50 provided, and a molded product is extruded from the movable mold 209 by the ejecting unit 300. The gist of the invention is not limited thereto. Configuration may be made in such a manner that a molded product is pressed by the plunger 118 provided in the injection unit 100 and the molded product is 55 extracted from the fixed mold 208.

Description Of Reference Numerals

- 100 injection unit
- 104 first injection servomotor
- 111 second injection servomotor
- 112 third injection servomotor
- 113 first arm
- 115 first connecting member
- 116 second arm
- 117 second connecting member
- 118 injection plunger
- 200 mold clamping unit
- 204 movable die plate

11

- 205 toggle link mechanism
- 206 mold clamping servomotor
- 207 crank mechanism
- 300 ejecting unit
- 301 ejecting plate
- 302 ejecting pin
- 303 ejecting servomotor
- 304 crank mechanism
- 400 control unit
- 401 motor drive circuit

The invention claimed is:

1. A die casting machine comprising: an electric servomotor for injection in a first stage, which is fixed to a motor mounting plate; a motion converting mechanism in the first stage, which converts rotational motion of the electric servomotor for injection in the first stage into rectilinear motion of a linear motion body; an electric servomotor for injection in a second stage, which is mounted on the linear motion body; a motion converting mechanism in the second stage, which converts rotational motion of the electric servomotor for injection in the second stage into rectilinear motion of an injection plunger; and a control unit which controls driving of the electric servomotors for injection; the die casting machine being characterized in that:

the control unit drives only the electric servomotor for injection in the first stage independently in a low-speed

12

injection step, and drives both the electric servomotor for injection in the first stage and the electric servomotor for injection in the second stage simultaneously in a high-speed injection step and a pressure intensification step.

5 2. A die casting machine according to claim 1, characterized in that: one of the motion converting mechanism in the first stage and the motion converting mechanism in the second stage is a crank mechanism which includes a first arm and 10 a second arm, the first arm being rotationally driven by the electric servomotor for injection in the first stage or the electric servomotor for injection in the second stage, the second arm having one end rotatably linked with the first arm and the other end rotatably linked with the linear motion body or the 15 injection plunger.

3. A die casting machine according to claim 2, characterized in that: an initial position of the crank mechanism is set so that the high-speed injection step can be carried out in a 20 rotational angle range of the first arm where a relative speed of the linear motion body or the injection plunger is the highest, and the pressure intensification step can be carried out in a rotational angle range of the first arm where a magnifying ratio of force acting on the linear motion body or the injection plunger is the highest.
